Attorney

UNITED STATES PATENT OFFICE.

ANTHONY NELSON, OF ST. PAUL, MINNESOTA.

CUE CHALKER.

Application filed November 21, 1925. Serial No. 70,543.

To all whom it may concern:

Be it known that I, ANTHONY NELSON, a citizen of the United States, residing at St. Paul, in the county of Ramsey and State of Minnesota, have invented new and useful Improvements in Cue Chalkers, of which the following is a specification.

It is my object to provide novel and efficient means for chalking the tips of pool or billiard cues.

A further object of my invention is to provide a device of this kind which is durable and inexpensive to manufacture.

My invention also includes various novel features of construction which will be more fully pointed out in the following specification and claims.

Referring to the accompanying drawings, which illustrate the best form of my device at present known to me, Figure 1 is a plan view of my improved cue chalker in its normal position on the guides; Fig. 2 is a side elevation of the same; Fig. 3 is a central vertical section of the device in operation, 25 a fragmentary portion of the cue being shown in position for applying the chalk to the tip; Fig. 4 is a detail elevation of one of the spring holders and Figs. 5 and 6 are side and end views, respectively, of the 30 spring detent which fits into the holder shown in Fig. 4.

My improved chalker is adapted to be secured to the under surface of the overhanging side rail on a pool or billiard table by 35 means of a pair of brackets 10 which are perforated at 11 to receive screws. A pair of guides 12, extending between and rigidly connected to the brackets 10, are provided to support the chalker proper. These guides 40 are circular in cross section and pass through suitable perforations in downwardly projecting ends 13 of a frame 14. The frame 14 is slidable longitudinally on the guides 12 and is formed with upwardly projecting 45 bearings 15 and a central aperture 16 in which a pair of guide pulleys 17 are mounted.

Pieces of cue chalk 18 are carried in a pair of containers 19 having bell-mouth 50 open ends 20. The containers 19 are formed with hubs 19^a which are rigidly secured to opposite ends of the supporting spindle 21. This spindle is revoluble in the bearings 15 and carries a spring housing 22 between said 55 bearings. A coiled spring 23, enclosed in the housing 22 around the spindle 21, is se-

cured at its ends to a pair of holders 24 (shown in detail in Fig. 4). These holders consist of a ring 25, which fits inside of the housing 22, and a pair of bars 26, united at 60 their ends to said ring and curved outward to straddle the spindle 21. One of the holders 24 is secured by a pin 27 to the housing 22 and spindle 21, and the other holder, which is secured to the opposite end of the 65 spring 23, is held against rotation by a detent 28. (See Figs. 5 and 6.) This detent comprises a collar 29 which fits over the spindle 21 and is formed with a pair of lugs 30. The detent 28 fits between and 70 engages the bars 26 of the adjacent spring holder 24, and also extends into the adjacent bearings 15, suitable key ways being cut in said bearing to receive the lugs 30. The 75 spring 23 is thus adapted to resiliently hold the spindle 21, and the containers 19, against rotation in the bearing 15.

A chain 31, consisting of a series of links fastened end to end by suitable ball joints, is wound on and secured at one end to a 80 drum 32 on the housing 22. The chain 31 passes downward between the guide pulleys 17 and its lower extremity is fastened by a pin 33 to the guides 12. The pulleys 17 are tilted so that the chain 31 in passing tangentially from said pulleys will pass tangentially to the drum 32. 85

Operation.

In use my improved chalker is mounted, 90 as described above, on a pool or billiard table or it may be placed on any suitable support near the table. The frame 14, carrying the chalk containers and operating mechanism is normally held near the middle of the 95 guides 12 (in the position shown in Figs. 1 and 2) by the action of the spring 23 which winds the chain 31 on the drum 32.

To chalk the tip of a cue, the cue is placed in horizontal position with its tip inserted 100 in the bell-mouth end 20 of the container at either end of the spindle 21, (see Fig. 3) the cue being indicated at 34. The cue is now thrust toward the chalker. This thrust slides the frame 14 longitudinally on the 105 guides 12 against the action of the spring 23 and actuates the chain 31 to rotate the containers 19 and chalk upon the tip of the cue. The frame 14, carrying the chalk containers and rotating mechanism, thus slides to the 110 end of the guides 12 and is stopped by the bracket 10. The cue 34 is now removed al-

- lowing the spring 23 to wind the chain 31 on the drum 32 and return the frame 14 to its starting position at the middle of the guides 12. Similarly, a cue tip may be chalked by 5 a short thrust in the opposite direction against the chalk in the other container 19. Thus, cues may be chalked rapidly and efficiently with minimum exertion on the part of the user.
- 10 Having described my invention what I claim as new and desire to protect by Letters Patent is:
1. A cue chalker comprising, a support, a frame 15 slidable on said support, a chalk container revolubly mounted on said frame, resilient means for holding said container against rotation on said frame and means for rotating said container against the action of said resilient means when said frame 20 slides on said support.
2. A cue chalker comprising, a support, a frame slidably mounted on said support, a chalk container revolubly mounted on said frame, a spring adapted to restrain rotation 25 of said container, and means for rotating said container against the action of said spring when said frame is caused to slide on said support, said rotating means comprising, a drum revoluble with said container and a chain wound upon and secured at one end to said drum, the other end of said chain being secured to said support.
3. A cue chalker comprising, a support, a frame 30 slidably mounted on said support, a chalk container revolubly mounted on said frame, a spring adapted to resiliently hold said container against rotation, a drum revoluble with said container, a chain wound upon and secured at one end to said drum, the other end of said chain being secured to said support and guide pulleys for said chain mounted in said frame.
4. A cue chalker comprising, a support, a frame 35 slidable longitudinally on said support, a spindle revolubly mounted in said frame, a chalk container rigidly mounted on said spindle, a coiled spring arranged to resiliently hold said spindle against rotation, a drum rigidly connected to said spindle and a chain wound upon and secured to said drum at one end and at the other end to said support.
5. A cue chalker comprising, a horizontal 40
- guide, a frame slidable longitudinally on said guide, a spindle revolubly mounted in said frame, chalk containers rigidly mounted on the ends of said spindle, a coiled spring arranged to resiliently hold said spindle against rotation, a drum rigidly connected to said spindle and a chain wound upon and secured to said drum at one end and at the other end to said guide. 55
6. A cue chalker comprising, guides, a frame slidable on said guides, a pair of bearings mounted on said frame, a spindle 60 revoluble in said bearings, a spring housing rigidly mounted on said spindle between said bearings, a coiled spring arranged in said housing to restrain rotation of said spindle and housing, chalk containers rigidly mounted on the ends of said spindle, a drum on said housing and a chain wound upon and secured at one end to said drum, the other end of said chain being secured to said guides. 65
7. A cue chalker comprising, a pair of horizontal guides, a frame slidable longitudinally on said guides, a pair of bearings on said frame, a spindle revoluble in said bearings, a spring housing rigidly mounted on said spindle between said bearings, a coiled spring arranged in said housing to restrain rotation of said spindle, chalk containers rigidly mounted on the ends of said spindle, a drum on said housing, a chain 70 wound upon and secured at one end to said drum, the other end of said chain being secured to said guides. 75
8. In a device of the class described, a 75 guide, a chalk container normally positioned near the middle of said guide and arranged to be moved toward either end thereof, and means for rotating said container when the same is moved toward either end of said 80 guide. 85
9. In a device of the class described, a horizontal guide, a pair of chalk containers open at opposite ends and arranged on said guide to be moved toward either end thereof, and means for rotating said containers when the same are moved toward either end of said 85 guide. 90
- In testimony whereof, I have hereunto signed my name to this specification.

ANTHONY NELSON.
